Primary Examiner — Maria J. Edwards(74) *Attorney, Agent, or Firm* — ALSTON & BIRD LLP(57) **CLAIM**

The ornamental design for eyewear, as shown and described.

DESCRIPTION

FIG. 1 is a perspective view of eyewear showing my new design;
FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof, the left side being a mirror image thereof; and,
FIG. 7 is a right side elevation cross-section view thereof taken along line 7-7 in FIG. 2.

The broken lines immediately adjacent shaded areas represent bounds of the claimed design and illustrate features of the eyewear that form no part of the claimed design. All other broken lines illustrate features of the eyewear that form no part of the claimed design.
